KEYING CONTROL SYSTEM

Reynold S. Chapin, Flushing, N. Y., assignor to
 Press Wireless, Inc., New York, N. Y., a corpora-
 tion of Delaware

Application July 8, 1946, Serial No. 681,820

1. Claim. (Cl. 250—27)

1 This invention relates to telegraph signalling systems and more particularly to channel keying control arrangements therefor.

A principal object of the invention is to provide improved electron tube and associated circuit arrangements for keying "on" and "off" two telegraph signalling channels.

Another object is to provide improved electron tube and associated circuit arrangements for keying "on" and "off" tone frequencies under control of impressed telegraph signals of the neutral type or of the polar type.

A feature of the invention relates to a novel combination of grid-controlled electron tubes for selectively connecting either one of two tone frequencies to a common output channel, under control of input telegraph signals either of the polar type or of the neutral type.

Another feature relates to a keying control arrangement for telegraph signalling systems and the like whereby a pair of input signals such for example as the tone frequencies, can be alternately switched to a common output circuit under control of polar or neutral telegraph signals, and requiring no balancing adjustment while preserving the output signal free from switching transients.

A still further feature relates to the novel organization, arrangement and relative interconnection of parts which cooperate to provide an improved tone keyer arrangement.

Other features and advantages not specifically enumerated will become apparent after a consideration of the following detailed descriptions and the appended claim.

In the drawing.

Fig. 1 is a schematic wiring diagram of a typical telegraph keying system embodying the invention.

Fig. 2 is a graph showing the types of signals to be keyed in the system of Fig. 1.

In the drawing, the terminals A and B represent input terminals on which are impressed respectively two different input signals. For example, these signals may be in the form of tone frequency voltages of different frequencies as represented by the signals A and B (Fig. 2). Thus the signal A may have a frequency of 2400 C. P. S., and the signal B, a frequency of 1200 C. P. S. The terminals C represent a common output channel which may be connected to a signal receiving or rekeying device 10 of any well-known type which is adapted to respond selectively to the two different frequencies A and B. Connected to terminals D is any well-known source of

2 telegraph signals 11 which produces either the neutral type of signal as represented by graph 12 where the signal voltage varies on one side of zero voltage, or a polar signal 13 which varies equally on opposite positive and negative sides of zero. It will be understood that the keying frequency of the signals applied to terminals D is lower than either of the frequencies A and B.

The signal A is applied through coupling condenser 14 between the cathode 15 of grid-control tube 16 and ground; whereas the signal B is applied between the control grid 17 of dual triode tube 18 and ground, by means of condenser 19. A suitable high resistance grid leak is provided in the usual manner between the grid 17 and ground. Consequently, the B signals applied to grid 17 are amplified in the first triode section of tube 18 and appear as corresponding output voltages across the plate load resistor 21. The second triode section of tube 18 has its control grid 22 connected in parallel with the control grid 23 of tube 16. The cathodes 24 and 25 are returned to ground through a common cathode load resistor 26. The plate or anode 27 is connected directly to the plus B terminal of the usual D. C. plate power supply (not shown).

With this connection of the triode sections of tube 18, this tube forms a limiter of the type disclosed in U. S. Patent #2,276,565 to which reference may be had for a further description of the operation thereof as a limiter. When no signals are applied from source 11 to the grid 23, the tube 16 is biased substantially to plate current cutoff by means of the fixed bias battery 28 and resistor 29. Under these conditions however, the triode section 17, 25, 30, is plate current conductive and permits the B signal applied at terminals B to be amplified and appear as corresponding amplified voltages across load resistor 21. In other words, as long as tube 16 is at cutoff, the signals at terminals B appear across the load resistor 21. Since the grid 23 is normally biased negatively with respect to its cathode to plate current cutoff, it is apparent that if a signal of the polar type and having a negative voltage value is applied to grid 23, this last-mentioned condition is not disturbed, with the result that the B signals continue to appear across the resistor 21. On the other hand, if a positive polar signal is applied to grid 23 or if an "on" positive neutral signal is applied to grid 23, the negative bias of tube 16 is overcome permitting plate current to flow through tube 16, resulting in the appearance of amplified A signals across resistor 21. At the same time, this positive input voltage

is applied to control grid 22, causing a large plate current to flow between anode 27 and cathode 24 and thence through the common cathode load resistor 26. As a result of this drop of voltage across resistor 26, the grid 11 is biased negatively to a sufficient extent to cutoff plate current flow between 30 and 25, thus positively cutting off the B signals from appearing across the resistor 21.

Before the positive voltage signal applied to grids 22 and 23 reaches a level sufficient to overcome the fixed bias resulting from battery 28, neither of the signals A or B appears across the common load resistor 21. As the positive voltage of the signal applied to grids 22 and 23 increases in amplitude, it finally overcomes the bias on the cathode 15 causing tube 16 to be plate conductive and the A signals appear across resistor 21. Thus, for a change in voltage at grid 23 from negative to positive polarity or from zero to positive polarity, the signal appearing across resistor 21 has changed from the signal B to the signal A. Furthermore, at an intermediate point of the positive signal applied to grid 23, neither signal A nor signal B appears across resistor 21.

In addition to the A and B signals which alternately appear across resistor 21, there is present the frequency of the signal applied to grid 23. For this purpose, the output terminals C are coupled to resistor 21 through a high pass filter which is designed to have its cutoff frequency located between the frequency of the input signals to grid 23 and the frequency of signal B which is the lower of the two signals A and B. As a result, only these signals A and B appear at the common output terminal C.

While in this specification and the appended claims, reference is made to the tubes as triodes, it will be understood that the term "triode" is used in its generic sense to include any grid-controlled tube having a control grid which can be suitably biased to control the "on" and "off" flow of plate current as is well-known in the art. Furthermore, while in the foregoing specification the sources A and B have been referred to as audio frequency tone sources, it will be understood that the invention is equally well usable with sources A and B of any other frequency range such as radio frequencies in which event of course the high pass filter will be designed to pass the radio frequencies from the sources A and B while suppressing or eliminating the key-

ing control frequencies from the source 11. The terminals C can then be connected to any suitable radio frequency power amplifier, thus enabling the system to be used for so-called carrier frequency shift transmission.

While one particular embodiment has been described, it will be understood that various changes and modifications may be made herein without departing from the spirit and scope of the invention.

10 What is claimed is:

An arrangement of the character described, comprising a first triode, a first source of input signals coupled to the cathode of said first triode, a second triode, a second source of input signals connected to the control grid of said second triode, a third triode having its control grid connected in parallel with the control grid of the first triode, a common load resistor connected between the cathodes of the second and third triodes and ground, means normally biasing the cathode of the first triode to plate current cutoff while the second triode is plate conductive, means to apply a control signal of a certain magnitude to the control grids of the said first and third triodes without disturbing the plate current cutoff of the first triode and the plate current conductivity of the second triode, and for applying a control signal of a different magnitude to the control grids of the first and third triodes to render the first triode plate conductive while simultaneously rendering the second triode non plate conductive through the intermediary of the voltages developed across said common cathode resistor, and a common plate load circuit connected to the plates of the first and second triodes.
